Hugo Junkers

UNITED STATES PATENT OFFICE.

HUGO JUNKERS, OF AACHEN-FRANKENBURG, GERMANY.

FLYING-MACHINE SUPPORTING SURFACE.

Application filed June 26, 1920. Serial No. 392,141.

(GRANTED UNDER THE PROVISIONS OF THE ACT OF MARCH 3, 1921, 41 STAT. L., 1313.)

To all whom it may concern:

Be it known that I, HUGO JUNKERS, a citizen of the German Empire, residing at Aachen-Frankenburg, Germany, have invented certain new and useful Improvements in Flying-Machine Supporting Surfaces (for which I have filed application in Germany, December 22, 1916; Germany, June 26, 1919; Austria, February 11, 1918; 10 Holland, July 29, 1919; Sweden, December 18, 1919; Switzerland, December 23, 1919; Denmark, December 31, 1919; Norway, January 17, 1920; Czechoslovakia, January 17, 1920), of which the following is a specification.

My invention refers to supporting surfaces for flying machines and more especially to all-metal surfaces of the self-supporting type, i. e. such as are not externally stayed or stiffened.

Now the customary manner of constructing the supporting surfaces of flying machines consists in covering a frame composed as a rule of two longitudinal beams 25 and a plurality of cross beams (frames or ribs) with a covering of cloth, or the like.

The essential drawbacks appertaining to this form of construction reside in the use of elastic material for the covering, which 30 at best is suitable for the transmission of tensile forces. Thus the fact of the covering being elastic renders it necessary, for example for the purpose of securing and maintaining the proper shape of the supporting surfaces, as also for taking up twisting strains to arrange a great number of cross beams or transverse girders, as a consequence of which the construction of the surface is rendered more difficult, and its 40 weight increased. Moreover, for the purpose of transmitting the forces of air resistance acting on the surface it is as a rule necessary to interpose a special connection resistive against air pressure between the longitudinal beams and the cross frames.

According to my present invention, now, the supporting surface has the form of a hollow body comprising a number of beams disposed in the longitudinal direction of the supporting surface and preferably constructed after the manner of lattice girders, and a sheet metal covering, entirely enveloping said girders, and provided with protruding portions such as corrugations, or

the like, extending in the direction of flight, 55 and serving to reinforce the covering, which latter is rigidly connected with the various parts of the frame at various points distributed all over the wing surface.

This novel form of wing construction involves a number of highly important advantages, as will be explained in full hereinafter.

Owing to the peculiar profile given to the sheet metal covering, the possibility is afforded of providing a cover, even with sheet metal of slight thickness, such as is required to avoid too large an increase in weight which possesses a sufficient rigidity of its own to enable it to transmit both the forces 70 coming to act on it perpendicularly and tending to deform the cross sectional shape of the supporting surface (such as air pressure, local loads, as when, for instance, the wing is being trod on), as also the forces 75 acting in the direction of the profile given to the sheet metal, and all this without any excessive alteration of shape and for relatively big distances. The fact that the improved cover constitutes in and for itself 80 a rigid body, renders it possible to transfer to it either partially or even entirely the functions which it was hitherto necessary to provide special members in the wing frame for.

For this reason, the transverse beams or girders (cross-frames, ribs) which were otherwise required for the purpose of securing the true cross sectional shape of the wing, for the mutual connection of the longitudinal beams, and for taking up the twisting strains, may now be dispensed with either in part or entirely. Besides, the covering may itself constitute the air pressure resisting connection between the 95 single longitudinal beams. By these means, the construction of the wing is simplified to a very considerable extent.

In the event of a member or section of the frame being damaged, the forces, which 100 would otherwise be taken up by this particular member or section, may be transmitted through the cover across the section damaged, or else transferred to adjoining portions of the frame, so that thereby the 105 safety of the novel supporting surface, even in the event of any section thereof being injured, is increased.

The main beams disposed in the longitudinal direction of the wing, are preferably constructed after the manner of panel works composed of tubes. Now, in accordance with the fact that the load diminishes towards the free ends of the supporting surfaces, the top and bottom flanges of said girders are suitably composed of members or sections of different diameter or different 10 wall thickness.

It will also be found expedient to so dispose the cover that the raised portions thereof, facing the inner side of the wing, will come to repose directly upon the top and 15 bottom flanges of the main girders. If the cover be then rigidly connected at every point of contact with the frame girders, say by rivets, then there will be created a very large number of fastening points uniformly 20 distributed all over the wing, as a result of which arrangement the carrying out of the aforementioned functions on the part of the covering is essentially facilitated.

Instead of forming a simple rivet connection at the points of contact between cover and frame members, it is obvious that also any other manner of connection may be selected, say for example by clamping.

In the case of supporting surfaces of the 30 kind hereinbefore described, the twisting (torsional) forces arising in the wing are also for the main part transmitted by the cover, which in this case is subjected to shearing stresses. In particular in the case 35 of large sized supporting surfaces, i. e. such wherein the distance between the longitudinal beams or girders is relatively large, it has been found that the sections of the wing covering located between two such beams or 40 girders on being subjected to great strains will more and more tend to lose their original shape, which will in one course lead to the wing cover bulging out and crumpling up. This drawback may be successfully 45 overcome by arranging between the longitudinal beams or girders on the corrugated sheet metal and firmly fastening to this latter, special stays in such wise that the said stays will cross the corrugations formed in 50 the wing cover either obliquely or vertically. The action of these stays is such that both in the case of locally confined strains as also in that of more extended strains exerted on the wing cover, the normally corrugated 55 shape, and therewith the power of resistance proper to the wing cover, cannot be prematurely impaired or lost.

By the provision of stays or stiffening members of the said kind, the wing covering is enabled to withstand increased shearing stresses. To utilize this fact to the utmost extent possible, and accordingly to be able to safely transmit even increased shearing forces from the cover to the point where 60 the wings are secured (wing base or girder 65

junction points), respectively, at the points of division between one wing section and another, the cover is suitably reinforced at the said points of connection or division by additional members serving for the transmission of forces, disposed in the plane of division of the wings or in the plane of the girder junction from girder to girder, that is to say, about vertically to the girders. 70

The front face of the wing, the so-called 75 wing head is not as a rule provided with a sharp edge, but is rounded off. As this rounded off portion possesses a rather small radius relatively to the profile formation of the remaining wing section, it is somewhat 80 difficult to bend the corrugated or otherwise shaped sheet iron into this particular form. It will therefore be found expedient to construct the wing head as a distinct part, duly 85 connected with the upper and lower portions 85 of the cover which are likewise constructed separately for themselves. In this connection, it is again possible to carry this out in manifold ways. Thus, for example, the 90 head may be primarily constructed after the 90 manner of a channel or groove, the internal extremely bent portion of which is level, while the two lateral portions, which are less 95 curved, are provided with corrugations, or the like, gradually increasing in depth toward the outside, and corresponding in shape to the profile formation of the wing 100 covering. However, the head of the wing may also be fitted out with through going corrugations or the like, formed by means 105 of special dies, or else by forging, or a similar operation. Finally, the profile formation of the wing cover may also be made to gradually run down to a level surface in the direction toward the junction point for the 110 head which, for its part, is in the main also level.

In the drawings affixed to this specification and forming part thereof several modifications of the subject matter of my invention are illustrated diagrammatically. In 115 the drawings—

Fig. 1 is a cross section of a supporting surface,

Fig. 2 a longitudinal section,

Fig. 3 a plan with part of the cover removed.

Fig. 4 is the cross section of another modification.

Fig. 5 is a side elevation of a longitudinal 120 beam or girder;

Fig. 6 is a cross section of a particular profile formation;

Figs. 7 to 12 are details showing the manner of attaching the corrugated or otherwise 125 shaped sheet metal to the frame girders;

Figs. 13 to 15 illustrate one modification of the terminal edge of the wing, while

Figs. 16 and 17 show a form of execution 130 of the head,

Figs. 18 to 20 illustrate a supporting surface construction, the corrugated sheet iron cover of which is provided with special stays in order to render the cover more capable 5 of resistance against torsional (shearing) stress.

Fig. 18 being a cross section of the supporting surface taken in the direction of flight on line I—I in Figs. 19 and 20;

10 Fig. 19 a plan taken on line II—II in Fig. 18, and

Fig. 20 a sectional view on line III—III in Fig. 18, taken in the longitudinal direction of the supporting surface.

13 Referring to the drawings, the frame arranged within the interior of the hollow supporting surface according to Figs. 1 to 3 consists of a relatively large number of longitudinal lattice girders, comprising a top 20 flange 1, a bottom flange 2, perpendicular stays 3, and diagonal stays 4. A cover 6 consisting of corrugated sheet metal is fitted across the frame, being rigidly jointed to the flanges 1 and 2 at the sunken portions 7 of the corrugations. The said cover thus 25 constitutes a substitute for the resisting connection otherwise required to be arranged between the single main girders of the frame for the purpose of taking up the forces that 30 come to act upon the supporting surface in a horizontal direction. Diagonal rods 5 are arranged to run from the bottom flange of the one longitudinal girder to the top flange of the adjacent girder, said rods, conjointly with cover 6, enabling the wing to take up 35 torsional stresses.

Fig. 4 is a cross sectional view of a wing similar to that shown in Fig. 1, the difference being that in this case the top and bottom flanges of the main girders are staggered so that the frame cross section will 40 be composed of approximately equilateral triangles. The top and bottom flanges 1 and 2, (Fig. 5) are composed of tubular members, the diameter of which gradually lessens 45 in the direction toward the wing end.

50 In the modification illustrated in Fig. 6, the profile formation is reinforced at certain points, distributed over the full length of the wing, for the purpose of rendering the cover still more capable of resistance against deformations, in other words to render the entire supporting surface still more rigid, without, however, essentially increasing the 55 weight thereof. The cover 6, possessing a profile formation of any kind whatsoever, and fixed to the frame section 1, is provided at certain intervals with projections 9, 10 either disposed along the outside over the 60 entire width of the wing, or else arranged within the wing between always two longitudinal girders; said projections, while having a greater depth, preferably resembling 65 in shape the general profile formation, and they may either be integral with the sheet

metal cover (as at 9), or else they may be superposed separately, as shown at 10. These projections may further be reinforced by providing them with corrugations in the manner shown at 11.

70 Fig. 7 illustrates a simple way of attaching the corrugated sheet metal cover 6 to a tubular frame member 1 by means of rivets 13 traversing the tube walls.

75 Figs. 8 and 9 show a different form of connection. In this case, a flat reinforcing strip 16 extending in the direction of the frame girder 1 is riveted from below to the sheet metal cover 6, this latter being also corrugated. In the sunken portions 7 of the corrugations, the strip 16 is rigidly joined to the clip 18, said clip being clamped to the frame member 1. By these means any weakening 80 of sections of the frame owing to the presence of rivet holes is avoided, while moreover the number of fastening points between the frame section and the cover is further increased, in consequence of which arrangement the distribution of force over the sheet metal cover is enhanced to a still 85 greater degree, and any danger of said cover being wrenched off is obviated.

90 A similar form of joint is shown in Figs. 10 to 12. In this case, a clip 20 serves to connect the sheet metal cover 6 to the frame member 1, the upwardly bent laps 21 of said clip being attached to the corrugated or otherwise shaped sheet metal in the vicinity of its neutral layer.

95 Figs. 13 to 15 illustrate one form of construction of the rear edge of the supporting surface. The corrugations formed in the upper section 25 and in the lower section 26 of the wing, respectively, are staggered for the distance of half a pitch relatively to each 100 other, so that the corrugations at the rear edge of the wing will converge to a sharp edge 27 running in a line with the corrugations of the wing cover. For the purpose of connecting the upper and the lower wing sections 25, 26 at the rear edge of the wing, both sheet metal sections are fixed to a wedge 28 of wood, or the like, in the faces 105 of which corrugations are formed corresponding to those of the wing cover.

110 Figs. 16 and 17 are, respectively, a cross section and a front view of a specially constructed head for a supporting surface, the front edge of which is rounded off, and corrugated or otherwise shaped for the extent 115 of its entire length. These corrugations, as seen from the front (Fig. 17), are disposed at an incline for the purpose of suitably staggering the profile formation of the upper and lower wing faces relatively to each 120 other in order to secure their converging 125 smoothly at the rear edge of the wing.

125 In the wing structure shown in Figs. 18 to 20, stays 30 are arranged along the lower wing face between the bottom flanges for 130

the purpose of increasing the resisting capacity of the sheet metal cover against torsional or shearing stresses. These reinforcing stays are disposed in a line with the 5 longitudinal beams, and similar to these, they are rigidly connected to the corrugated sheet metal, say by riveting. In the example illustrated, the cross sectional shape of these stays is that of a corrugation, however, 10 also other cross sectional forms may be made use of. In the case of large sized supporting surfaces there may be arranged between each pair of longitudinal girders a plurality of stays of this kind, and these latter may 15 be provided with special props supporting them relatively to the girders. Thus, for instance, the reinforcing stay of the central field is propped up by means of the rods 33 relatively to the oppositely disposed top flange common to the adjoining 20 longitudinal girders.

According to requirement either all, or else only some of the corrugated sheet metal sections disposed between the longitudinal 25 girders may be provided with such reinforcing stays.

The reinforcing members 31 disposed in a line with the corrugations are connected at the junction point of the wing with the edge 30 of the corrugated sheet metal, the ends of said members being connected to the bottom flanges 2, which thus effectively assist the wing cover in transferring the shearing forces on to the points of junction with the 35 longitudinal beams. The aforesaid reinforcing members may, moreover, be arranged, as shown in the drawing, either only between always two longitudinal girders within the fields or wing sections 40 subjected to the greatest amount of strain, or else around the entire cross sectional area of the wing.

In a like manner, other hollow bodies 45 pertaining to air craft, and subjected to stress in the same way as the supporting surfaces, such as rigid rudder surfaces (so-called fins) and the like, may be constructed in a similar manner, in accordance with this invention.

50 I claim:

1. In a flying machine surface in combination, a plurality of longitudinal girders and a sheet metal covering surrounding the said girder structure and connected therewith in a plurality of places, said sheet metal covering being provided with narrow corrugations substantially uniformly extending in the direction of flight over the entire length of said covering.

60 2. In a flying machine surface in combination, a plurality of longitudinal girders converging towards each other and having each one flange in common with the adjacent girder and a sheet metal covering sur-

rounding the said girder structure and connected therewith in a plurality of places. 65

3. In a flying machine surface in combination, a plurality of longitudinal girders converging towards each other and having each one flange in common with the adjacent girder and a sheet metal covering surrounding the said girder structure and connected with the top and bottom flanges, respectively, of said girders. 70

4. In a flying machine surface in combination, a plurality of longitudinal girders, a corrugated sheet metal covering surrounding the said girder structure, a corrugated reinforcing member closely applied to the inner side of said covering and clamping 80 means adapted to connect said covering with said girders. 75

5. In a flying machine surface in combination, a plurality of longitudinal girders and a sheet metal covering surrounding the said girder structure and connected therewith in a plurality of places, said sheet metal covering being provided with corrugations substantially extending in the direction of flight, the corrugations on the upper and lower portions of the covering being staggered in such a way as to form a keen edge at the rear end of the said surface. 85 90

6. In a flying machine surface in combination, a plurality of longitudinal girders and a sheet metal covering surrounding the said girder structure and connected therewith in a plurality of places, said covering being provided with corrugations substantially 95 extending in the direction of flight, the corrugations on the upper and lower portions of the covering being staggered in such a way as to form a keen edge at the rear end of said surface, and the rounded head portion being formed of a separate piece of 100 plain sheet metal. 105

7. In a flying machine surface in combination, a plurality of longitudinal girders and a sheet metal covering surrounding the said girder structure and connected therewith in a plurality of places, said covering being composed of a plurality of separate parts, the rounded head portion formed of plain sheet metal and the top and bottom 115 portions formed of corrugated sheet metal, said portions being fixed to each other in any suitable manner. 110

8. In a flying machine surface in combination, a plurality of longitudinal girders 120 and a sheet metal covering surrounding the said girder structure and connected therewith in a plurality of places, said covering being composed of a plurality of separate parts, the rounded head portion and the top 125 and bottom portions fixed to each other in any suitable manner, said top and bottom portions being provided with corrugations.

staggered in such a way as to form a keen edge at the rear end of said surface, while the said head portion has corrugations formed thereon which extend in an oblique 5 direction so as to connect the staggered corrugations of the said top and bottom portions.

9. In a flying machine surface in combination, a plurality of longitudinal girders, 10 longitudinal stiffening members extending substantially in parallel with and between said girders and a sheet metal covering surrounding the said girder structure and said stiffening members and connected to both said girders and said stiffening members in a plurality of places.

10. In a flying machine surface in combination, a plurality of longitudinal girders, 15 longitudinal stiffening members extending substantially in parallel with and between said girders, a sheet metal covering surrounding the said girder structure and said stiffening members and connected therewith in a plurality of places and stays between 20 said stiffening members and the opposite flanges of said girders.

with corrugations substantially extending transversely to said girders surrounding said girder structure, and stiffening members extending substantially in parallel with 25 and between said girders, said covering being fixed to said girders and said stiffening members.

11. In a flying machine surface in combination, a plurality of longitudinal girders, 30 longitudinal stiffening members extending substantially in parallel with and between said girders, a sheet metal covering surrounding the said girder structure and said stiffening members and connected therewith 35 in a plurality of places and stays between said stiffening members and the opposite flanges of said girders.

In testimony whereof I affix my signature.

HUGO JUNKERS.
